THOMAS A. REID, OF WILKINSBURG, PENNSYLVANIA, ASSIGNOR TO WESTINGHOUSE ELECTRIC & MANUFACTURING COMPANY, A CORPORATION OF PENNSYLVANIA.

ELECTRIC-RESISTANCE FURNACE.

Application filed February 23, 1922. Serial No. 538,541.

To all whom it may concern:

Be it known that I, THOMAS A. REID, a citizen of the United States, and a resident of Wilkinsburg, in the county of Allegheny and State of Pennsylvania, have invented a new and useful Improvement in Electric Resistance Furnaces, of which the following is a specification.

My invention relates to electric furnaces and particularly to electric resistance furnaces and it has for its object to provide a relatively simple structure for relatively small electric resistance furnaces, comprising a relatively small number of relatively large shaped parts to permit of easily and quickly assembling and disassembling the entire furnace.

In practising my invention, I provide an open-end and open-top thin sheet metal casing and a thin sheet metal top plate having reinforcing side members. I provide a plurality of blocks of refractory material placed inside of said open-ended casing in a predetermined order and so shaped and placed as to provide a furnace chamber. I provide a plurality of relatively thin refractory plates each having a plurality of small spaced-apart, aligned, integral projections on one surface thereof, to constitute the lining of the furnace chamber, and a resistor member operatively engaging that side of the refractory plate on which the small, integral projections are located. I provide further a front and a rear metal plate having embodying means for operatively engaging and interlocking with the front and rear edges of the casing and of the top plate and a plurality of bolts located in the corners of the metal casing for clamping the front and the rear plates against the casing and the top plate, and for holding the refractory blocks in proper operative position longitudinally of said casing. The front plate is provided with an opening through which the thin refractory plates and the resistor may be placed in proper operative position in the furnace structure and heat insulating plates are located back of the front plate to maintain the thin refractory plates in their proper operative position longitudinally of said furnace chamber.

In the single sheet of drawings, Figure 1 is a view, in vertical lateral

cross-section, of an electric resistance furnace embodying my invention, and illustrated as located on an assembling fixture.

Fig. 2 is a vertical longitudinal section of a furnace embodying my invention, taken on the line II—II of Fig. 3;

Fig. 3 is a front view of a furnace embodying my invention, and

Fig. 4 is a partial sectional view thereof taken on line IV—IV of Fig. 3.

An electric furnace, designated generally by the numeral 11, comprises a thin sheet metal casing 12 having open ends and bent to substantially U-shape. In order to maintain the casing 12 in its preformed shape during the process of assembly of the furnace, it may be placed upon a fixture comprising a substantially horizontally extending bench or platform 13, upon which are placed two jaws or clamps 14 which may be either adjustably located thereon by any suitable means or may be provided with adjusting means comprising a substantially stationary block 15 secured to the top of the platform 13 and an adjusting screw 16, the inner end of which bears against the outer surface of one of the jaws or clamps 14. This construction of the assembly fixture permits of employing the same fixture for a number of different widths of furnace casings.

After the open-ended and open-topped casing 12 is located between the adjustable jaws 14, two longitudinally extending clamping rods 17 are placed in the corners of the casing. A refractory brick or block 18 of a suitable heat insulating material, having its lower corner portions cut away to provide chambers 19 in which the rods 17 may fit, is placed upon the bottom of the casing 12, its width being such as to fit closely between the sides of the casing. Then, two side blocks 21 and 22 of substantially the same material as the block 18, are placed on edge upon the member 18 with their outer surfaces engaging the respective inner surfaces of the sides of the casing 12. A brick or block 23 of a suitable high-temperature resisting refractory material is next placed upon the block 18 and between the blocks 21 and 22, and blocks 24 and 25 of similar refractory material are placed on edge upon the block 23 and inside of the blocks 21 and 22. Next, a refractory block 26, of sub-

- stantially the same material as the blocks 23, 24 and 25, is placed flat-wise on the upper edges of the blocks 24 and 25, the block 26 being of such width as to fit closely between the inner surface of the blocks 21 and 22, and of such thickness as to bring its upper surface in substantially the same plane as the upper edges of the blocks 21 and 22. A block 27, substantially the same in material and dimensions as the block 18, is then placed upon the block 26 and the upper edges of the blocks 21 and 22, the blocks 27 being of such thickness as to bring its upper surface substantially flush with the upper edge of the sides of the casing 12. Two rods 17 are placed in chambers 19 provided in the upper corners of the block 27 substantially as hereinbefore described in connection with the block 18. The longitudinal position of all of the blocks is substantially as indicated in Fig. 2 of the drawing, there being a space left between the rear end of the blocks 23, 24, 25 and 26 and the rear edge of the casing and a relatively smaller space left between the blocks 18, 21, 22 and 27 and the rear edge of the casing. A top plate 28 of thin sheet metal having reinforcing members 29, of substantially L-shape in lateral cross-section secured thereto at its sides, is placed upon the block 27, the downwardly extending portions of the members 29, being located outside of, serving to hold the upper edges of the sides of the casing 12 in proper operative position.
- A block 30 of a suitable high temperature resisting refractory material is placed in its proper operative position with the inner face thereof in abutting relation to the rear end surfaces of the blocks 23, 24, 25 and 26, the block 30 being of such thickness that its rear surface is substantially flush with the rear edge of the blocks 18, 21, 22 and 27, as illustrated in Fig. 2 of the drawing. A relatively thin plate 31 of a refractory heat-insulating material, or of asbestos lumber, is then placed in position abutting not only against the rear portions of the plates 18, 21, 22 and 27, but also against the rear surface of the plate 30. The thickness of the plate 31 is such as to bring its rear surface substantially flush with the rear edge of the casing 12 and of the top plate 28.
- A rear end plate 32, having an opening 32^a therethrough, is placed in its proper operative position against the outer surface of the plate 31, its other dimensions being such as to cause it to fit closely within the metal casing. The plate 32 has an inwardly extending flange or bead 33 located in such position thereon as to lie outside of the edge of the casing 12 and of the top plate 28, to thereby retain these relatively thin sheet metal members in their proper operative position relatively close against the outer surfaces of the blocks 18, 21, 22 and 27. A front

plate 34 is then placed in its proper operative position at the front of the furnace structure with its inner face abutting against the front end surfaces of the hereinbefore mentioned longitudinally extending refractory bricks or blocks. The front plate is provided with an outer flange 35 and an inner flange or bead 36, to be located respectively on the outside and on the inside of the sheet metal casing 12 and of the top plate 28 at the front ends thereof, to securely hold them in their proper operative positions relatively to the outer set of refractory blocks hereinbefore described. Nuts 37 may be screwed upon the threaded outer end portions at the front and at the rear of the rods 17 to securely clamp the front and rear end plates, not only against the casing 12 and the top plate 28, but also against the refractory blocks hereinbefore described. After the nuts 37 have been tightened on the rods 17, the furnace structure is substantially self-supporting and may be removed from the assembling fixture hereinbefore described, if desired. The front plate 34 is provided with a substantially rectangular opening 38 substantially coextensive with, in outline, the lateral dimensions of a furnace chamber 39 constituted by the refractory bricks or blocks assembled as hereinbefore described.

In order to provide a removable muffle or lining for the furnace chamber, as well as a resistor-supporting means, I place a plurality of relatively thin refractory plates 41 in spaced-apart relation in the furnace chamber 39, each plate having a plurality of relatively small spaced-apart, alined, integral projections 42 on one surface thereof. These plates may be provided with shouldered edge portions, substantially as illustrated in Fig. 1 of the drawing, to permit of interlocking the same to maintain them in their proper operative position within the furnace chamber, although this feature is not an essential one and any suitable method may be employed for maintaining them in their proper operative position within the furnace chamber. A resistor member 43 operatively engages that surface of the plates 41 having the integral projections and may comprise any suitable or desired form of metallic resistor member of such resistance that the length of resistor member employed will permit that amount of current to flow which is necessary to heat the chamber to a predetermined temperature when the ends 44 of the resistor are connected to a suitable source of supply (not shown). Any desired method of bringing out the ends 44 through openings 45 in the furnace structure may be employed. Any suitable or desired interconnection of the various resistor members 43, located at the bottom, side and top of the furnace chamber may be employed. The thin refractory plates and the co-operating

resistor member are more particularly described and claimed in application Serial No. 449,685, filed March 5, 1921, by O. A. Colby and myself and assigned to the Westinghouse Electric & Manufacturing Company, to which reference may be had for further details.

A rectangular block 46 of asbestos lumber is placed immediately in front of the block 10 26 and back of the front plate 34, the lower edge of the plate 46 being immediately in front of the front edge of the front top refractory plate 41, substantially as illustrated in Fig. 2 of the drawing. Two vertically-extending, relatively narrow, rectangular bars or plates 47 of asbestos lumber, are located in front of the front edge of the blocks 24 and 25, their upper ends supporting the plates 46 and their lower ends resting upon 20 a horizontally extending plate 48 of asbestos lumber, the upper edge of which is substantially flush with the upper surface of the bottom plates 41. The front plate 34 is provided with a forwardly projecting ledge or 25 shelf 49, the top of which is a relatively small distance below the bottom of the refractory plate 41 constituting the bottom lining of the furnace chamber, and has located thereon a horizontally extending plate 30 51 of asbestos lumber, suitably secured thereto by means of bolts 52.

Vertically extending outside members 53 are bolted against the front plate 34 immediately adjacent to the sides of the furnace chamber 39 by a plurality of bolts 54, each member 53 having an inner offset or shoulder portion 55 to provide a guide for a door 56 comprising a metallic casing 57 which is filled with, or which has its inner surface lined with, a plurality of bricks or slabs 58 of a suitable refractory material. A sight opening 59 is provided in the door member 56, normally closed by a cover member 61 loosely secured on the casing 57. A 45 bracket 62 may be secured against the front plate 34 at one side thereof upon which may be mounted any suitable or desired mechanism which is operative to permit of raising and lowering the door 56 from its normal 50 operative position illustrated in Fig. 3 of the drawing to permit of placing material within and removing it from, the furnace chamber 39.

If it becomes necessary to remove the resistor member 43 because of damage thereto or to remove one of the plates 41, it is only necessary to remove the plate 51, the plate 48, the plates 47 and the plate 46, after which any or all of the plates 41 may be removed 60 from the furnace chamber 39 through the opening 38 in the front plate, it being understood, of course, that the door 56 has been moved upwardly or taken off entirely.

The hereinbefore described construction 65 and method of assembling provides an elec-

tric resistance furnace comprising relatively few parts which are assembled in predetermined order and which may, therefore be assembled and disassembled in relatively short periods of time and which structure 70 is provided with means for securely interlocking the various parts thereof in such manner that a relatively compact furnace structure is obtained, the parts of which shall, at the same time, maintain their proper 75 operative positions during the operation of the furnace and shall also permit of shipping the complete furnace without danger of damage thereto.

Various modifications may be made in the device embodying my invention without departing from the spirit and scope thereof and I desire that only such limitations shall be placed thereon as are imposed by the prior art or are specifically set forth in the 85 appended claims.

I claim as my invention:

1. An electric furnace structure comprising an open ended and open top metallic casing, a removable metallic top plate for said casing interlocked therewith, an outer base plate, two spaced apart outer side plates, and an outer top plate inside of said metallic casing, all of said plates being of refractory heat-insulating material, an inner base plate, a pair of spaced-apart inner side plates and an inner top plate, all located inside of said heat-insulating plates and comprising refractory high-temperature resisting material, and spaced apart to provide a furnace chamber, and a heating element for said furnace chamber comprising a plurality of relatively thin refractory plates 90 95 constituting a lining for said furnace chamber and a resistor member held in proper operative position in said furnace structure by said thin refractory plates in co-operation with the plates constituting the inner lining.

2. An electric furnace structure comprising an open ended and open top metallic casing, a removable metallic top plate for said casing interlocked therewith, an outer base plate, two spaced apart outer side plates and an outer top plate inside of said metallic casing, all of said plates being of refractory heat insulating material, an inner base plate, a pair of spaced-apart inner side plates and an inner top plate, all 100 105 located inside of said heat-insulating plates and comprising refractory high-temperature resisting material, and spaced apart to provide a furnace chamber, a heating element for said furnace chamber comprising a plurality of relatively thin refractory plates 110

115 120 125 130 constituting a muffle or lining for said furnace chamber, a resistor member held in proper operative position in said furnace structure by said thin refractory plates in co-operation with the plates constituting the

4
inner lining, and front and rear metallic end plates interlocked with said metallic casing and casing top.

3. An electric furnace structure comprising an open ended and open top metallic casing, a removable metallic top plate for said casing interlocked therewith, an outer base plate, two spaced apart outer side plates and an outer top plate inside of said metallic casing, all of said plates being of refractory heat-insulating material, an inner base plate, a pair of spaced-apart inner side plates and an inner top plate, all located inside of said heat-insulating plates and comprising refractory high-temperature resisting material, and spaced apart to provide a furnace chamber, a heating element for said furnace chamber comprising a plurality of relatively thin refractory plates constituting a muffle for said furnace chamber and a resistor member held in proper operative position in said furnace structure by said thin refractory plates in co-operation with the plates constituting the inner lining, front and rear end plates interlocked with said metallic casing and casing top, and a plurality of bolts for holding said end plates against the end of said casing, casing top and said inner and outer base, side and top plates.

4. In a quickly mountable and demountable furnace structure, in combination, an open end and open top metallic casing, an outer and an inner refractory base plate located on the bottom of said casing, spaced-apart outer and inner refractory side plates supported respectively by the outer and inner base plates, outer and inner refractory top plates supported respectively by the outer and inner spaced-apart side plates, a metallic top plate supported by and interlocked with the sides of the metallic cas-

ing, front and rear end plates interlocked with the casing and casing top, and a plurality of bolts for clamping said front and rear end plates against said casing and casing top, said bolts being maintained in spaced-apart relation in said metallic casing by said refractory outer base and top plates.

5. In a quickly mountable and demountable furnace structure, in combination, an open end and open top metallic casing, an outer and an inner refractory base plate located on the bottom of said casing, spaced apart outer and inner refractory side plates supported respectively by the outer and inner base plates, outer and inner refractory top plates supported respectively by the outer and inner spaced-apart side plates, a metallic top plate supported by and interlocked with the sides of the metallic casing, front and rear end plates interlocked with the casing and casing top, a plurality of bolts for clamping said front and rear end plates against said casing and casing top, said bolts being maintained in spaced-apart relation in said metallic casing by said refractory outer base and top plates, a plurality of relatively thin refractory plates constituting the muffle of the furnace chamber located inside of said inner refractory plates and supported by said inner base plate, and a plurality of refractory heat insulating plates located between said front end plate and said thin refractory plates for maintaining said thin refractory plates in proper operative position longitudinally of said furnace.

In testimony whereof, I have hereunto subscribed my name this 20th day of February 1922.

THOMAS A. REID.
